AXLE BOX

Filed Dec. 22, 1925

Harry S. Vincent Inventor

By his Attorney
Symmes & Schinner

UNITED STATES PATENT OFFICE

HARRY S. VINCENT, OF RIDGEWOOD, NEW JERSEY

AXLE BOX

Application filed December 22, 1925. Serial No. 77,057.

My invention relates to vehicle axle journal boxes, and is especially well adapted for the driving boxes of locomotives. The invention is especially concerned with axle boxes of the general type shown in my application, Serial No. 548,939, filed April 3, 1922. I aim to facilitate maintenance and repair of such boxes, especially as regards the wearing surfaces of their bearings. I also aim to obviate or minimize any tendency toward spreading of the box sides. How these and other advantages can be realized through the invention will appear from my description hereinafter of a selected and preferred embodiment.

In the drawings:

Fig. 1 is partly a side elevation and partly a vertical mid-section, showing a journal box embodying my invention in place in the pedestal of a locomotive side frame,—the view being taken from the inner side of the box (i. e., the side toward the other side frame of the locomotive).

Fig. 2 is a fragmentary view showing the bearing in vertical axial section as indicated by the line 2—2 in Fig. 1.

The box shown in the drawings comprises a box structure 10 having at its sides or limbs 11 and 12 the usual flanges 13, providing grooves. The pedestal jaws 14 of the locomotive frame engage in these grooves and serve as guideways for up and down movement of the whole journal box. The box structure 10 is of a general yoke or U shape; but instead of being inverted (as in the usual prior constructions), the U is arranged erect (right side up) about the axle 15, with the transverse member 16 a short distance beneath the axle. The structure 10 is supported by being suspended (as it were) from the separate bearing generally and comprehensively designated as 17, which rests on the axle 15 between the side members 11, 12.

As thus far described, the construction is substantially like that shown in my above-mentioned application Serial No. 548,939.

As illustrated, and described in my said application, the bearing 17 is one single part,—removable only as such, and requiring or

worn so as to be incapable of repair. In accordance with my present invention, I divide the bearing 17 into a crown piece 18 in direct contact with the axle 15, and a backing piece or retainer 19 thereabove. This division is 53 preferably along a circular arc substantially concentric with the bearing surface of the part 19. Preferably the abutting cylindrical surfaces of these parts 18 and 19 are provided with engagement means for preventing 60 movement or shifting of either relatively to the other lengthwise of the axle 15; as shown the crown piece 18 has a broad, shallow groove 20 extending circumferentially around its exterior, and the backing piece 19 has a corresponding ridge 21 accurately fitting between the edges of the groove. If desired, the bearing piece 18 may be of brass, or of duralumin or other light metal, and faced with babbitt; while the back piece 19 may be 70 of steel to afford strength. Shoulders 22 extend inward from either side 11, 12 of the box structure 10 at its upper end, and the backing has corresponding shoulders 23 which cooperate with the shoulders 22 in the support of the box structure 10 by the bearing 17. The parts 18 and 19 are of such general width as to fit (snugly but not tightly) between the sides 11, 12 below the shoulders 22, while the upper portion of the 75 part 19 is of such reduced width as to fit (snugly but not tightly) in the opening between the shoulders 22; i. e., the bearing 17 corresponds substantially to the internal width of the box 10. Owing to the entire 80 absence of lateral enlargement of the parts 18, 19 below the shoulders 23, any tendency of these parts to spread the box sides 11, 12 by upward wedge action is avoided. At the lower end of the part 18 of the bearing 17, 85 on either side, is a central downward-projecting lug 24 adapted to engage and fit snugly in a recess 25 in the ridge 26 on the corresponding side member of the box structure 10, so as to prevent movement of the bearing 17 90 in the box structure lengthwise of the axle 15. Removable tapering pin or key members 27 engaged between the shoulders 22 and 23 normally wedge the bearing 17 fast in the 95 box structure 10, maintaining the lower ends 100

of the part 18 firmly seated against shoulders formed by the upper sides of the ridges 26, with the lugs 24 engaged in the recesses 25. As shown in Fig. 1, the cooperating shoulders 22, 23 of box and bearing slope upward and outward away from the axle, so that under the pressure on them they cooperate (through the interposed correspondingly surfaced keys or wedges 27) to hold the box sides 11 and 12 together as against any spreading tendency. The keys or wedges 27 may be powerfully forced home and held in place by tightening up nuts 28 on bolts 29 that extend through laterally projecting apertured lugs 30 on the ends of the wedges. The heads 31 of the bolts 29 lie in undercut recesses at the inner ends of grooves in the side members 11, 12 of the box structure 10. The load or weight of the locomotive may be freely received by the bearing 17, independently of the box structure 10, through the opening between the shoulders 22, 23 of the latter. As shown in Fig. 2, the bearing 17 has recesses 32, 33 in its upper side for receiving corresponding projections on the spring saddle (not shown). The outer faces of the box 10 and the bearing structure 17 are flush with one another, and afford lateral bearing surfaces all the way around the axle opening for engaging the driver wheel hub (not shown) and taking the side or "end" thrust from the wheel. Below the axle 15, the lateral bearing is afforded by a transverse flange or web 35 integral with the box sides 11, 12 and its bottom 16, and forming an end wall for the space inside the box.

In the box 10, between its bottom 16 and the axle 15, is a sheet metal lubricator device or cellar 40, shown as of the general Elvin type. This cellar 40 has a perforated lubricating plate 41, curved in conformity to the axle 15, with its ends bent outward to engage beneath inturned flanges 42 at the upper edges of the box sides, and a follower plate 43 for sustaining a superjacent grease cake against the plate 41. This follower plate 43 is urged upward toward the axle 15 (and the lubricating plate 41) by a spiral compression spring 44 beneath it, acting against the box bottom 16, which may be recessed at 45 to accommodate the spring. Preferably, the sides and bottom of the box 10 are recessed to form transverse ridges or ways 46, 47, 48 adjacent the top and the bottom of the cellar 40. These ways keep the cellar in a definite position, yet offer little frictional resistance to its insertion or withdrawal at the open inner end of the box. The cellar 40 may be secured in place by means of a horizontal retainer bar or pin 55 extending through apertured lugs 56 on the members 11, 12, and itself secured by one or more keys 57.

In order to remove the crown bearing 17 from the journal box 10, it is only necessary to relieve the bearing of the spring tension and lift the spring saddle (not shown) out

of engagement with the recesses 32, 33, withdraw the wedges 27, and drop the box sufficiently to disengage the bearing 17 therefrom at 24, 25. Having been disengaged from the box 10 by vertical displacement therein as just described, the bearing 17 may be removed from the box by simply moving the bearing endwise of the axle 15. When the box structure 10 is to be removed from the locomotive frame in order that its hub face may be relined (or for any other reason), it is only necessary to remove the bearing 17 as just described, drop the frame pedestal binder 14 so as to open the lower ends of the guideways 14, and allow the box structure 10 to slide or drop down from the axle 15,—the opening between the shoulders 22, 23 at the upper end of the box structure being of width sufficient to pass the shaft readily, though of less width than the bearing 17 as a whole.

With the bearing 17 all one part, as in my prior application, it was necessarily quite heavy and difficult to handle in inserting it in the box or removing it. Moreover, making this unitary bearing 17 entirely of bearing metal, such as bronze, made it very expensive. With the bearing 17 in two parts 18, 19 as above described, it is easier to handle and much less expensive, because the backing or retainer 19 can be of cast steel, and only the crown piece 18 need be of bronze. Accordingly, the periodic rebabbiting of the bearing surface is greatly facilitated; and either of the parts 18, 19 is much less expensive to replace (when occasion arises) than a one-piece bearing 17 all of bronze would be. There is no sacrifice of strength in the divided bearing 17, either as regards its function of "spreader" to prevent pinching in of the box sides 11, 12, or as "tie" to hold the sides together against any spreading tendency (due to the tendency of the bearing to turn with the axle, for example): on the contrary, the strength is if anything rather augmented, because of the use of steel in the retainer 18. With respect to these functions of the retainer 18, indeed, it may be regarded as virtually part of the box structure rather than as a bearing part.

What I claim is:—

1. A vehicle axle journal box construction comprising an upward-open yoke-shaped box with downward and inward-sloping lateral shoulders, and a bearing resting on the axle having upward and outward sloping lateral shoulders, and securing members engaged between corresponding shoulders of box and bearing to prevent relative displacement of the latter.

2. The combination with an open-topped yoke-shaped axle box, of a retainer having means for supporting the box and a bearing between the retainer and the axle, said box having means engaging said bearing to prevent axial displacement thereof and said bear-

ing having means engaging said retainer to prevent axial displacement of the retainer.

3. A vehicle axle journal box construction including a box structure with a laterally shouldered opening at its upper end of width sufficient to pass the axle; an axle bearing structure in said box structure of greater width than said opening including a backing member and a bearing member, both of said members being removable from the box structure by movement lengthwise of the axle; and means for normally preventing such movement.

4. A vehicle axle journal box construction including a box structure with a laterally shouldered opening at its upper end of width sufficient to pass the axle; and an axle bearing structure in the box structure of greater width than said opening including a backing member and a bearing member, said members being removable from the box structure by movement lengthwise of the axle, said bearing member being normally kept from such lengthwise movement by engagement with the box structure, but being displaceable vertically in the latter to disengage it and permit its removal as aforesaid.

5. A vehicle axle journal box construction including a box structure with a laterally shouldered opening at its upper end of width sufficient to pass the axle; an axle bearing structure in the box structure of greater width than said opening including a backing member and a bearing member, said members being removable from the box structure by movement lengthwise of the axle, said bearing member being normally kept from such lengthwise movement by engagement with the box structure, but being displaceable vertically in the latter to disengage it and permit its removal as aforesaid; and interengagement means on said bearing and backing members normally preventing relative axial displacement thereof.

6. A vehicle axle journal box construction including a box structure with a laterally shouldered opening at its upper end of width sufficient to pass the axle; a bearing structure in the box structure of width greater than said opening including a laterally shouldered backing member and a bearing member, both of said members being removable by movement lengthwise of the axle, said bearing member being normally kept from such lengthwise movement by engagement with the box structure, but being displaceable vertically in the latter to disengage it and permit its removal aforesaid; and a removable member normally engaged between the aforesaid shoulders of said box structure and of said backing member to prevent the aforesaid disengagement of the bearing member.

7. A vehicle axle journal box construction including a box structure with a laterally shouldered opening at its upper end of width

sufficient to pass the axle; a bearing structure in the box structure of width greater than said opening including a laterally shouldered backing member and a bearing member, both of said members being removable by movement lengthwise of the axle, said bearing member being normally kept from such lengthwise movement by engagement with the box structure, but being displaceable vertically in the latter to disengage it and permit its removal aforesaid; a removable member normally engaged between the aforesaid shoulders of said box structure and of said backing member to prevent the aforesaid disengagement of the bearing member; and means on said backing member engaging cooperating means on the bearing member normally preventing the aforesaid movement of the bearing member lengthwise of the axle.

In testimony whereof I have hereunto signed my name.

HARRY S. VINCENT.
